(57) **CLAIM**

The ornamental design for a front portion of a hip, ridge or rake roofing shingle, as shown and described.

DESCRIPTION

FIG. 1 is a front, top and left side perspective view of a front portion of a hip, ridge or rake roofing shingle showing our new design;

FIG. 2 is a rear, top and right side perspective view thereof; FIG. 3 is a right side elevational view thereof; the left side is a mirror image thereof;

FIG. 4 is a front elevational view thereof;

FIG. 5 is a rear elevational view thereof;

FIG. 6 is a top view thereof;

FIG. 7 is a bottom view thereof; and

FIG. 8 is a front, top and left side perspective view of a second embodiment of a front portion of a hip, ridge or rake roofing shingle;

FIG. 9 is a rear, top and right side perspective view thereof;

FIG. 10 is right side elevational view thereof; the left side is a mirror image thereof;

FIG. 11 a front elevational view thereof;

FIG. 12 is a rear elevational view thereof;

FIG. 13 is a top view thereof; and,

FIG. 14 is a bottom view thereof.

The broken lines depict environment only and do not form any part of the claimed design.

The irregular lines on the top, right, left and edge surfaces are to illustrate surface irregularities generally.
